UNITED STATES PATENT OFFICE.

RUSSELL A. SMITH, OF PORT HOPE, MICHIGAN.

DESIGN FOR A MONUMENT.

Application filed January 9, 1922. Serial No. 118. Term of patent 14 years.

To all whom it may concern:

Be it known that I, RUSSELL A. SMITH, a citizen of the United States of America, residing at Port Hope, in the county of Huron and State of Michigan, have invented a new, original, and ornamental Design for a Monument, of which the following is a specification, reference being had to the accompanying drawings, forming a part hereof.

The figure is a perspective view showing my new design for a monument.

I claim:—

The ornamental design for a monument as shown.

RUSSELL A. SMITH.
